DESIGN FOR A DOUBLE COVE LIGHTING FIXTURE

Irol G. Gangbin, Fresno, Calif.

Application March 26, 1948, Serial No. 145,388

Term of patent 14 years

(Cl. D48—23)

To all whom it may concern:

Be it known that I, Irol G. Gangbin, a citizen of the United States, residing at Fresno, in the county of Fresno, and State of California, have invented a new, original, and ornamental Design for a Double Cove Lighting Fixture, of which the following is a specification, reference being had to the accompanying drawing, forming a part thereof.

Figure 1 is a bottom plan view of a double cove lighting fixture, showing my new design.

Figure 2 is a side elevational view of the double cove lighting fixture.

Figure 3 is an enlarged diametral sectional view of the same.

Fig. 4 is a perspective view of the double cove lighting fixture, looking from below.

The dotted line showing of the fluorescent tubes shown in Fig. 3 is for illustrative purposes only.

I claim:

The ornamental design for a double cove lighting fixture, as shown and described.

IROL G. GANGBIN.
